ERIC G. LINDHE, OF HASTINGS UPON HUDSON, NEW YORK

IMPROVED SPRING CONSTRUCTION

Application filed July 26, 1932. Serial No. 624,694.

This invention relates to spring devices and has particularly to do with springs for vehicles such as automobiles.

An object of the invention is to provide a simple, efficient strong economical spring unit.

A further object is to provide a spring unit in which the deflections of the unit load variations will be much more uniform throughout the unit than has hitherto been the case and to thereby avoid undue strain of the unit and the ensuing breakage.

A still further object is to provide a spring unit which responds uniformly throughout to load applications and which can be readily and easily adjusted to various normal loads and to check excessive deflections beyond predetermined limits in either direction.

Yet a further object is to provide a simple construction which is an improvement on the construction shown in my co-pending application Ser. No. 591,653, filed Feb. 8, 1932.

Further and more specific objects, features, and advantages will more clearly appear from a consideration of the specification hereinafter when taken in connection with the accompanying drawings which form part of the specification and which illustrate a present preferred form of the invention.

Briefly considered the invention comprises a leaf element fastened at one point to a relatively fixed member and at another point to a relatively movable member and having disposed between the leaf element and the fixed member a plurality of compression elements movable with the leaf element and cooperating with each other and the fixed member to uniformly resist the movement of the spring and to effect a uniform distortion of the leaf throughout its length and regardless of the load applied. These compression plates are spaced with respect to each other along the leaf and have associated therewith interposed resilient pads.

In a preferred form of the invention a full length semi-elliptic spring leaf is employed mounted at its middle to the axle of a vehicle and supporting the body of the vehicle at its respective ends. Throughout the length of

the leaf element are disposed and supported therefrom a plurality of spaced compression plates preferably dependent from the leaf and having the interposed pads therebetween.

These plates and their pads are associated on each side of the fixed member attached to the axle and are held in predetermined state of pressure by means of connectors passing through the apertures in the plates, these connectors being adjustable to control the movement of the unit in either direction. Preferably these connectors have bolts on their outer ends to regulate the normal degree of pressure placed on the plates and pads along their outer portions to control the resistance to movement of the spring in one direction. These connectors are also operatively related to a cam mechanism adjustably connected to the body of the vehicle so that as the position of the body varies with respect to the spring this cam mechanism is operated to proportionally vary the position of the cam and consequently vary the pressure of the connector on the plate especially along the outer portion of the plates.

The lower portions of the plates and pads are subjected to compression by means of adjustable elements bearing against the ends of the plate units extending between these ends and the ends of the spring leaf as hereinafter described.

The preferred form of the invention is shown in the drawings, of which:

Fig. 1 is a side elevation of the device mounted on a vehicle;

Fig. 2 is a longitudinal vertical section through the device;

Fig. 3 is a longitudinal section taken through the cam mechanism;

Fig. 4 is a vertical cross-section taken on the line 4-4 of Fig. 2; and

Fig. 5 is a vertical cross-section taken on the line 5-5 of Fig. 1 showing the construction of one of the compression plates.

As shown in the drawings, the present preferred form of the device comprises a leaf spring 10. This leaf spring is fastened in any suitable manner at one end to a shackle 13 mounted on a frame element 14 of the vehicle. The other end of the spring element

is fastened at 12 directly to the end of the frame element 14. The axle 15 is disposed beneath a box-like hollow casing 16 which is held in position on the axle by means of transverse plates 17 and bolts 18 held in position by nuts 19 disposed beneath the flanges 20 of the axle. The spring member 10 is also disposed beneath the transverse plates 17 and is thus held in position on top of the casing 16, 10 as shown. The sides of the casing 16 are provided with openings 21 through which extends a shaft 22 having connected to one end thereof a crank arm 23 connected to a rod 24 attached to the frame element 14 and having 15 therein a turn buckle 25 to adjust the length of the rod 24 in the usual manner. The shaft 22 throughout its length within the casing 16 is formed sectionally in the form of a cam shape 26, shown in Fig. 2, and as this shelf is 20 rotated this cam shape is adapted to act upon the ends 27, 28, and 29 of connecting rods 30 and 31, the opposite ends of which extend beyond the compression plates and are adjustable as to their normal pressure by means of 25 nuts 32. The end 27 of the connector 30 is in the form of an eye and the ends 28 and 29 of the connector 31 are in the form of a pair of eyes acting somewhat as a yoke. From the arrangement and construction shown in the 30 drawings, it will be observed that when the cam shaft rotates in one direction the connector rods 30 and 31 will be drawn back and when the cam shaft moves in the opposite direction the connector rods will be pushed 35 apart. The rotation of the cam shaft is effected by and is proportional to the movement of the rod 24 in response to the relative movement between the spring unit and the frame member 14 of the vehicle. Suitable washers 40 33 and 34 and set screw 35 cooperate with the casing 16 and the cam shaft 22 to hold this portion of the mechanism in position.

Suspended from the spring member 10 are disposed a plurality of compression plates 36. 45 These compression plates as shown in Fig. 5 have an intermediary opening 37 to permit the passage of the connector rods and at the top have suitable fingers 38 spaced from the main body of the plate to permit these plates 50 to be slipped into the spring element 10 in a lateral manner. Their detailed construction is shown more fully in my copending application above mentioned.

Disposed between the lower ends of the respective and successive compression plates 55 36 are pads of rubber 39 or other suitable resilient or compressible material. These pads may be held in position in any suitable manner. Adjacent each end of the box 16 are 60 plates 40 and 41 which extend fully from the top of the unit to the bottom of the axle as shown and adjacent the outer ends of the series of compressible plates are plates 42 and 43 having lower turned offset portions 44 and 65 45. These plates 40 to 43, inclusive, act as

end plates for the respective series of compressible plates and pads. Plates 42 and 43 take the pressure from the nuts 32 and the connector rods at their lower end also take pressure from flat bars 46 and 47 which are disposed in an inclined position, as shown. The bar 46 extends from a lip 48 on a yoke 49 fastened to one end of the spring element 10, in any suitable manner, to the lowermost portion of the plate 42. Thus the position with respect to the lower end of the plate 42 is adjustable by means of a simple wedge 50, the position of which is adjusted by a set screw 51 and a lower off-set portion 44 of the plate 42. Flat bar 47 at the other end of the unit extends from the flat end of the spring 10 which acts as a shoulder downwardly to the lower end of the plate 43 and is adjustable in the usual manner similar to the adjustment of plate 46 and by similar mechanism. 70 75 80 85

In the operation of the device, the compression plates 38 are slid into position on the spring elements 10 with the rubber pads 39 between and along the lower edges and the nuts 32 on the ends of the connector rods 30 and 31 are tightened up to make it assume the normal load position shown in Fig. 1. Screws 51 are tightened up to cause the pressure bars 46 and 47 to bear against the lower ends of the series of compression plates with desired pressure and the cam shaft rocker arm 23 is connected to the rod 24 and the turn buckle 25 adjusted for the normal position of the rocker arm. 90 95

In this position of the parts the compression or strain on the unit is normal throughout. As the vehicle body tends to move down relative to the spring or axle this would tend to expand the upper ends of the compression plates and compress the lower ends. This compression of the lower ends is exerted through the compression bars 46 and 47. Undue expansion of the upper end of the compression plates 38 is prevented by the fact that the rocker arm 23 is moved counter-clockwise by its connection with the rod 24 and the cams 26 act to draw the connector rods 30 and 31 together to resist too great a spreading of these plates at their upper ends. When the frame 14 tends to move upward beyond normal position away from the axle this would tend to compress the upper ends of the compression plates 38 and expand the lower ends. This compression of the upper ends is relieved somewhat by the clockwise movement of the rocker arm 23. This device is simple of construction and assembly and simple and efficient in its operation. The actions and reactions of the spring and its associated parts with respect to the frame are checked in both directions by the cooperation between the compression bars 46 and 47 on the one hand, the operation of the cam shaft and the connector rods through the intermediary of the rod 24 on the other hand. 100 105 110 115 120 125 130

This, therefore, provides a construction in which too great reactions in the spring in either direction are promptly and efficiently checked without the use of extra and additional and expensive parts. The construction is such that the spring and its associated parts are hung or supported very low on the axle so that this spring can be applied to cars with low clearance while yet operating efficiently.

While the invention has been described in detail and with respect to a present preferred form thereof it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

What is claimed, is:

1. A vehicle spring device which comprises a spring leaf element, a plurality of spaced compression plates supported on said element, resilient material disposed between said compression plates, a frame connected to said spring element, connecting rods associated with said compression plates, a cam mechanism connected between the connecting rods and the frame and adjustable in accordance with the movement of the frame with respect to the spring element.

2. A vehicle spring device which comprises a spring leaf element, a plurality of spaced compression plates supported on said element, resilient material disposed between said compression plates, a frame connected to said spring element, connecting rods associated with said compression plates, a cam unit connected to the adjacent ends of the connecting rods, a rocker arm on said cam unit and a connection between the rocker arm and the frame of the vehicle.

3. A vehicle spring device which comprises a leaf element fixed at one point and free to move at a spaced point, a plurality of compression plates spaced along said leaf element between said points and suspended therefrom, resilient material disposed between said compression plates, connecting rods associated with said plates and at adjacent ends, a cam unit operatively associated with said adjacent ends and a connection between the cam unit and the frame of the vehicle whereby the cam unit is moved as relative movement takes place between the frame and the spring leaf.

4. A vehicle spring device which comprises a leaf element, a fixed member on which said element is fastened at one point, a plurality of compression plates suspended from and along said leaf element, resilient material disposed between said compression plates, means for adjustably holding said plates to-

gether in cooperative relation with the fixed members, a cam unit operatively connected to said means and a connection between the cam unit and the frame of the vehicle.

5. A vehicle spring device which comprises a leaf element fastened at its middle to a fixed member and free for movement at opposite ends, a plurality of compression plates disposed along and suspended from said leaf element on opposite sides of said fixed member, a resilient material disposed between said compression plates, means for adjustably holding said plates in cooperative relation with each other on the fixed member, a cam unit operatively associated with said means, and a connection between the cam unit and the frame of the vehicle whereby the cam unit is moved as relative movement between the frame and the spring element takes place.

6. A vehicle spring device which comprises a spring leaf element, a fixed member to which a portion of said element is fastened, a plurality of spaced apertured plates disposed along and suspended from said leaf element on one side of said fixed member, resilient material disposed between said suspended plates, means for adjustably compressing said plates together toward said fixed member, a cam unit connected to said means, and a connection between the cam unit and the frame of the vehicle whereby the cam unit is moved as relative movement takes place between the frame and the spring leaf.

7. A vehicle spring device which comprises a leaf element, a fixed member to which a portion of said element is fastened, a plurality of compression plates supported and suspended from said leaf element on at least one side of said fixed member, resilient material disposed between said compression plates, said plates having a plurality of sets of aligned openings therein, an adjustable connector passing through said openings and adapted to adjustably hold said plates together and press them towards the fixed member, cam means associated with said connector to predetermine the normal and abnormal limits of movement of the device and a connection between said cam unit and the frame of the vehicle.

8. A vehicle spring device which comprises a leaf spring, a plurality of spaced compression plates supported on said element, resilient material disposed between said plates, means connecting said plates to resist and check the movement thereof in either direction, cam means associated with said means and a connection between the cam unit and the frame of the vehicle.

9. A vehicle spring device which comprises a spring leaf element fastened at its mid-portion on top of an axle, a plurality of compression plates suspended therefrom on opposite sides of said axle, resilient material between said compression plates, said com-

pression plates having aligned openings therein, connector rods extending through said openings toward each other, and adjustable means on the outer ends of said rods to adjust the pressure of said rods on said series of compression plates, a cam unit associated with the inner adjacent ends of said connector rods, and a rotatable connection between the cam unit and the frame of the vehicle.

10. A vehicle spring device which comprises a spring leaf element fastened at its mid-portion on top of an axle, a plurality of compression plates suspended therefrom on opposite sides of said axle, resilient material between said compression plates, said compression plates having aligned openings therein, connector rods extending through said openings toward each other, and adjustable means on the outer ends of said rods to adjust the pressure of said rods on said series of compression plates, a cam unit associated with the inner adjacent ends of said connector rods, and a rotatable connection between the cam unit and the frame of the vehicle, and adjustable compression bars extending from the outer end of the spring leaf element and bearing against the lower ends of the outer compression plates.

30. 11. A vehicle spring device which comprises a single spring leaf element fastened at its mid-point on top of an axle, a series of compression plates suspended along said leaf element on opposite sides of the axle, resilient material disposed between the lower end portions of said compression plates, said compression plates having aligned openings therein, connector rods extending through said openings, a cam shaft operatively connected to the inner adjacent ends of said rods, adjustable nuts on the outer ends of said rods bearing against the outer plates of said series of compression plates, a rocker arm on the cam shaft, and an adjustable rod connecting the rocker arm to the frame of the vehicle.

12. A vehicle spring device which comprises a single spring leaf element fastened at its mid-point on top of an axle, a series of compression plates suspended along said leaf element on opposite sides of the axle, resilient material disposed between the lower end portions of said compression plates, said compression plates having aligned openings therein, connector rods extending through said openings, a cam shaft operatively connected to the inner adjacent ends of said rods, adjustable nuts on the outer ends of said rods bearing against the outer plates of said series of compression plates, a rocker arm on the cam shaft, and an adjustable rod connecting the rocker arm to the frame of the vehicle, compression bars extending from the outer ends of the spring leaf element downward toward the lower ends of the outer com-

pression plates of the series and means for adjusting these compression bars.

Signed at New York in the county of New York and State of New York this 25th day of July, A. D. 1932.

ERIC G. LINDHE.
